Inventor;
Thomas Wosser.

THOMAS WOSSER, OF SAN FRANCISCO, CALIFORNIA.

Letters Patent No. 87,813, dated March 16, 1869.

IMPROVEMENT IN STEAM-ENGINE VALVE-GEAR.

The Schedule referred to in these Letters Patent and making part of the same.

To all whom it may concern:

Be it known that I, THOMAS WOSSER, of the city of San Francisco, in the county of San Francisco, and State of California, have invented a new and useful machine for holding up the levers, and allowing the steam to follow the piston to the termination of the stroke, for the style of engines known as "Western-river engines," technically called a "gag," and I do hereby declare that the following is a full, clear, and exact description of the construction and operation of the same, reference being had to the annexed drawings, making a part of this specification.

To illustrate more clearly the application of my invention, I give three views of an engine, two of which show the application of the "gag" and its several parts.

Figure 1 is a side elevation, showing the "gags" *a a*, stand *b*, connecting-rod *c*.

Figure 2 is an end elevation of engine.

Figure 3 is a plan of engine, showing the "gags" *a a*, stand *b*, connecting-rod *c*.

Figures 4, 4, 4, show the "gag" on an enlarged scale. The peculiar form of this arm must be modified for the different engines it may be applied to.

Figure 5 shows the journal-pin for "gag" *a* put in stand *b*.

Figures 6, 6. Stand *b*, to support the "gag" *a*.

Figures 7, 7. Connecting-rod *c*.

To enable others skilled in the art to make and use my invention, I will proceed to describe its construction and operation, with the advantages to be derived by its use.

As regards the construction, the drawings are marked and lettered, so that any mechanic can construct the various parts of the "gag" by reference to the same; and for its operation and advantages, I would say that it can be applied to any steam-engine using side levers, as well as to new engines built with reference to this arrangement.

The general form of its various parts may be modified, to suit space and distance.

The objects obtained by this invention are—

First, it enables the engineer to attach the "gag" while the engine is in motion, to give any requisite amount of steam, and obviate the use of "folding cams" on the engine-shaft, enabling the engineer to graduate the steam to the load on the steamboat, and draught of water of the same, and can be as readily detached, the whole arrangement being adjusted by turning the screws *d d*, with the fingers, to the desired height, and securing them in place with the thumb-screw *e*, the top of screws *d* being chambered out, and a piece of rubber inserted, to "cushion" the levers on.

Second, by inspection of the drawing, it will be seen that the motion to the "gags" is communicated from the shaft that is worked by the exhaust-valve cam, and the screws must be so adjusted as to allow the steam-valve to seat in advance of the corresponding exhaust-valve, while the "gags" take their motion from the full-stroke cam. The effect produced is far better than using a full-stroke cam direct, the "gag" being always adjustable, and, when not required, can be screwed down clear of the levers.

I do not claim the connecting-rod, or the arms, or screws, independently.

What I claim as my invention, and desire to secure by Letters Patent, is—

The combination and arrangement of the arms *a*, the stand *b*, with the journal-pin *f*, the connecting-rod *c*, the screws *d*, with their rubber cushion *g*, and thumb-screw *e*, substantially as set forth.

THOMAS WOSSER.
